UNITED STATES PATENT OFFICE.

FRANK A. SHARPNECK, OF CHICAGO, ILLINOIS, ASSIGNOR TO THE WIZARD MANUFACTURING COMPANY OF MICHIGAN, OF ST. JOSEPH, MICHIGAN, A CORPORATION OF MICHIGAN.

CARBURETER.

1,096,569.

Specification of Letters Patent. Patented May 12, 1914.

Application filed March 17, 1913. Serial No. 754,842.

To all whom it may concern:

Be it known that I, FRANK A. SHARPNECK, a citizen of the United States, and a resident of the city of Chicago, county of 5 Cook, and State of Illinois, have invented certain new and useful Improvements in Carbureters, of which the following is a specification.

My invention relates to improvements in 10 carbureters and has for its object the provision of an improved carbureter which is of simple construction and efficient in operation.

The invention consists in the combinations 15 and arrangements of parts hereinafter described and claimed.

The invention will be best understood by reference to the accompanying drawings forming a part of this specification, and in 20 which—

Figure 1 is a top plan view of a carbureter embodying my invention, Fig. 2, a side elevation of the same, Fig. 3, a section of said carbureter taken on line $x-x$ of Fig. 2, 25 and Fig. 4, a section taken on line $y-y$ of Fig. 2.

The preferred form of construction as illustrated in the drawings comprises a suitable float chamber 1 in which is arranged an ordinary form of annular cork float 2 carried by an operating lever 3 which controls the operation of a valve stem 4 and through said valve stem the operation of an admission valve 5 which controls the entry of fuel 30 to said float chamber through an ordinary nipple 6, as will be readily understood by those skilled in the art. Float chamber 1 is provided with a removable cover 7 carrying a centrally arranged hollow stem 8 which 35 projects above and below said cover and through a central opening in the bottom of float chamber 1 as shown in Fig. 3. A nut 9 is threaded on the lower end of stem 8 and abuts the bottom of chamber 1, a suitable 40 packing being interposed between said nut and the bottom of chamber 1. This arrangement constitutes a simple and effective construction for assembling the parts.

A throttle valve chamber 10 is arranged 45 at the upper end of stem 8, said throttle valve chamber, stem and cover 7 being made integral with each other. A throttle valve 11 of any usual or desired construction is arranged in chamber 10 and is operated by 50 means of a shaft 12 extending through a

wall of said chamber in the usual manner. An annular valve seat 13 is arranged in the lower portion of chamber 10 and air openings 14 lead therefrom, as shown. Arranged in chamber 10 is a hollow valve head 15 adapted to seat upon valve seat 13 and control the passage of air therethrough, said valve head carrying a depending hollow valve stem 16 which operates in stem 8 and projects below the bottom thereof. The 60 lower end of valve stem 16 carries a threaded adjusting nut 17 which imprisons a spring 18, said spring serving to yieldingly hold valve 15 to its seat. By this arrangement it will be observed that as the suction of the 65 engine increases on high speeds, valve 15 will be raised from its seat proportionately to the increase of such suction and said speed of the engine, thus permitting the introduction of a proportionately greater amount of 70 air to valve chamber 10 and thence to the 75 engine.

A substantially U-shaped fuel supply pipe 19 leads from the bottom of float chamber 1 upwardly into valve stem 16, the upper terminal 20 of said tube being arranged 80 slightly above the normal fuel level in float chamber 1. A tortuous passage 21 is arranged in the bottom of chamber 1 to permit the passage of fuel to pipe 19, as shown in 85 Fig. 3, said passage being controlled by a needle valve 22 which is threaded in float chamber 1 and is provided with a stuffing box 23 to prevent leakage. An operating arm 24 is threaded on the outer end of valve 90 stem 22 and is adjustably secured thereon by means of a lock nut 25. Arm 24 is provided with a slot 24' and an operating lever 26 is secured centrally to shaft 12 and is provided with a smaller slot 27 coöperating 95 with the slot 24'. A sleeve 28 is fitted within slot 24' and abuts against the outer face of lever 26, said sleeve being secured in position by means of a bolt 29 passing therethrough and snugly fitting slot 27 in lever 100 26, said parts being adjustably secured in position by means of a nut 30 threaded on the inner end of bolt 29. By this arrangement, it will be observed, that sleeve 28 may be adjustably locked in position on lever 26 105 and slide in slot 24', thus constituting an operative connection between lever 26 and arm 24 for controlling the needle valve 22 and consequently the passage of fuel to pipe 19. By means of the lock nut 25 the posi- 110

tion of arm 24 may be adjusted on needle valve 22, and by means of bolt 29 and nut 30 the operative relation between lever 26 and arm 24 may be varied, thus furnishing means for quickly and delicately adjusting the amount of opening of needle valve 22 upon opening of throttle valve 11. This opening of needle valve 22 automatically furnishes the additional amount of fuel necessary for high speeds of the engine as will be readily understood.

Lever 26 carries two arms 31 and 32 formed integrally therewith and projecting at right angles to each other on opposite sides of a stop lug 33 formed on the outer side of valve chamber 10. Arm 31 carries a set screw 34 adapted to contact with lug 33 when throttle valve 11 is open. By this arrangement it will be observed, that the throttle valve 11 will be stopped at open or closed positions, and that the closed position of said throttle valve may be adjusted as desired. This constitutes a simple and efficient arrangement for the purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. In a carbureter, a float chamber having an opening in its bottom; a removable cover for said float chamber provided with a tubular stem projecting above and below it and

passing through the opening in the bottom of said float chamber; a nut threaded on said stem and abutting the bottom of said float chamber; a throttle valve chamber on said stem having an air valve seat therein; an air valve in said valve seat; a hollow stem depended from said valve and extending through said tubular stem; a nut threaded on the lower end of said hollow stem; and a spring around said hollow valve stem between said last mentioned nut and said tubular stem, substantially as described.

2. In a carbureter, a float chamber having an opening in its bottom; a removable cover for said float chamber provided with a tubular stem projecting above and below it and passing through the opening in the bottom of said float chamber; a nut threaded on said stem and abutting the bottom of said float chamber; a throttle valve chamber on said stem having an air valve seat therein; an air valve in said valve seat; a hollow stem depended from said valve and extending through said tubular stem; a nut threaded on the lower end of said hollow stem; a spring around said hollow valve stem between said last mentioned nut and said tubular stem; and a U-shaped fuel supply tube having one leg portion connected with said float chamber and its other leg portion disposed concentrically in said hollow valve stem, the upper end of said other leg being open, substantially as described.

In testimony whereof I have signed my name to this specification in the presence of two subscribing witnesses.

FRANK A. SHARPNECK.
